UNITED STATES PATENT OFFICE

2,669,143

LID LIFTING TOOL

Ray C. Bradbury, Alcomdale, Alberta, Canada

Application June 6, 1952, Serial No. 292,045

1 Claim. (Cl. 81—3.46)

1

The present invention relates to bottle and jar openers, generally speaking, and has more particular reference to an improved hand tool or implement which is expressly adapted to open bottles and jars by easily disconnecting the cap or lid.

An object of the invention is to structurally, functionally and otherwise improve upon similarly constructed and performing lid lifters and, in so doing, to provide a construction in which manufacturers and users will find their respective requirements and general needs aptly and satisfactorily met.

Another object of the invention is to provide a lid lifting tool whose construction is such that there are no sharp points or dangerous cutting edges to gash or cut the hands and fingers of users. Also, the tool is such that the user will rarely encounter breaking or chipping of glass, will find the tool always ready for use with no movable parts to adjust or wear out, will find the tool easy to apply, remove and otherwise such in construction that it will remove various types and sizes of lids from glass containers and will, in addition, perform satisfactorily in removing crown caps from beverage bottles.

In carrying out the invention, a tool is provided which is characterized by a substantially flat rigid bar member, the same being provided at one end with a prying and lifting hook, being provided intermediate its ends with a complementary shoulder or abutment for said hook, being also provided intermediate its ends with an oppositely extending abutment which coacts with a second prying and lifting hook at the opposite end of the bar member.

Then, too, novelty is predicated upon the stated construction wherein the bar member is provided at the last-named end not only with a selectively usable hook but is provided, in addition, with a pair of converging fingers which themselves terminate in additional hooks which coact with the adjacent hook and provide means for effectively and easily removing a crown cap.

Other objects, features and advantages will become more readily apparent from the following description and the accompanying sheet of illustrative drawings.

In the drawings:

Figure 1 is a fragmentary sectional view of a jar with a gasket-equipped lid showing the improved tool and the customary manner in which it is used in prying the lid loose and removing it;

Figure 2 is a top plan view of the structural arrangement seen in Figure 2 with the tool appearing in full and dotted lines respectively to

show the manner in which it may be satisfactorily used;

Figure 3 is a view showing the fragmentary portion of one end, the right hand end, of the tool and the manner in which the same is used as a lifter and remover for crown caps;

Figure 4 is an end elevation of the tool per se showing the same in a direction from right to left in Figures 1 to 3 inclusive.

Referring now to the drawings, attention is directed to Figure 1 wherein the numeral 6 denotes a food containing jar having a reduced neck with a lip portion 8, the lid being denoted at 10 and having a channel rim portion 12 with a packing ring or gasket 14 sealed and seated on said lip or mouth 8. The tool comprises a rigid flat elongated bar which may be described as a lever 16. The narrower left hand portion 18 is bent upon itself as at 20 and then is return bent to define what may be called the first lid prying and lifting hook 22. The free or terminal of this, which may be called either the bill or beak, is beveled and slightly rounded in plan as denoted at 24. As a matter of fact, it will be observed that the bend 20 is slightly oblique to the longitudinal axis of the bar and hence said hook 22 may be said to be offset. Struck out from the opening 26, and bent laterally and preferably slightly fluted, is an abutment or shoulder forming prong 28. This combines with the hook means 22. By placing the bill portion of the hook means 22 in a position for prying the gasket up and off of the jar neck and then swinging the tool in a direction from the dotted line position to the full line position the prong or stop comes against the marginal edge of the lid and the rotary or swinging action thus produced "drives" the beak of the hook in between the gasket and lip 8 whereupon the lid is dislodged and lifted for easy removal, as is obvious.

40 In case one is called upon to remove a lid of a larger diameter than is accommodated by the hook 22 and prong 28 it is possible to selectively use the second hook which embodies a shank 30, a return bend 32 and a wedge shaped and suitably sharpened bill or beak 34. It will be noticed that this hook 32 is bent in a direction opposite to the hook 22. In other words, one hook may be said to be bent down and under the lever and the other bent up and over the lever. 50 The latter hook 32 therefore combines or functions in conjunction with the upwardly bent prong 36. The latter is likewise struck out from the opening means 38 and is the same in shape and form as the prong 28. It follows that selectively usable hooks 22 and 32 are provided at

opposite ends of the rigid lever and prongs 28 and 36 are provided intermediate the ends the prong 28 combining with the hook 22 and the prong 36 combining with the hook 32. Then to, additional lifting elements are provided. These take the form of spaced depending fingers 40 at the hook end 32 and said fingers terminate in lifting hooks 42 which conveniently engage the flange 44 of a crown cap 46 on the neck 48 of a beverage bottle or the like 50. This is shown in Figure 3 wherein it will be observed that the bend of the hook 32 at this time constitutes a fulcrum for the hooked fingers 40. It will be also noticed in Figure 2 that the fingers 40 converge toward each other so that the hooks 42 toe in properly to accommodate the arc or curvature of the skirt of the crown cap 46.

It is further to be noted that the hooked fingers 40 depend in one lateral direction below what may be conveniently called the lower side of the lever in the drawings while the complementary fulcrum forming hook means 40 is directed in an upward direction.

The manner in which the hook means 22 and complementary stop 28 function is brought out in Figures 1 and 2. Where the hook 32 and complementary prong 36 are used the picturization would be the same except that the latter features 32 and 36 are for a lid of a greater diameter, as is evident. As far as the crown cap lifter is concerned this is clearly shown in the illustration in Figure 3.

It is thought that persons skilled in the art to which the invention relates will be able to obtain a clear understanding of the invention after con-

sidering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

A lid lifting tool comprising an elongated rigid bar member adapted to be used as a pry lever and adapted to span a container closing lid, said bar member being provided at one end with a laterally extending hook and being further provided intermediate its ends with a laterally extending abutment cooperating with said hook, said hook and abutment depending from the same side of the bar member and being spaced apart a predetermined distance slightly less than the diameter of the lid which is to be placed between the hook and abutment to be lifted, said hook being laterally offset in respect to the longitudinal axis of the bar member and provided with a feather-edged bill portion.
